UNITED STATES PATENT OFFICE.

JUSTUS A. TRAUT, OF NEW BRITAIN, CONNECTICUT, ASSIGNOR TO THE STANLEY RULE AND LEVEL COMPANY, OF SAME PLACE.

POCKET-RULE.

SPECIFICATION forming part of Letters Patent No. 387,570, dated August 7, 1888.

Application filed April 17, 1888. Serial No. 270,972. (No model.)

To all whom it may concern:

Be it known that I, JUSTUS A. TRAUT, a citizen of the United States, residing at New Britain, in the county of Hartford and State of Connecticut, have invented a certain new and useful Improvement in Pocket-Rules, of which the following is a specification.

My invention is in that class of rules for making linear measurements that are capable of being folded into compact form for convenience in carrying; and the object of my improvement is to conveniently lock the two principal members of such rules in an angular position, so that such a tool may serve the double purpose of rule and square or bevel.

In order to explain my said invention more clearly, I have annexed hereto a sheet of drawings, in which—

Figure 1 is a plan view of a four-fold rule embodying my invention. Fig. 2 shows the same opened to form a square. Fig. 3 shows the main hinge of said rule with the upper plate, 3, cut away to expose the middle hinge-leaf. Fig. 4 is an enlarged view of the hinge end of the rule cut away on line $x x$ of Fig. 1.

The rule here illustrated is identical in general construction with twenty-four-inch pocket-rules as commonly made, and therefore needs no detailed description. The several hinged members of said rule are indicated in the drawings by reference-figures 2, 3, 4, and 5. The main or central hinge of said rule is formed of a plate, a , secured to member 2, and of corresponding plates, b b' , inclosing said plate a and secured to the companion member, 3, these hinge parts being connected by a central pivot, c .

The plate a is provided with a hole, d , and the top plate, b , with a hole, d' , said holes being so located relative to each other that when the members 2 3 of the rule are opened

at a right angle, as in Fig. 2, these holes are coincident. In order to lock said parts together and thus form a square, I have provided in the free end of the member 5 a pin, 45 e , which, as said member is folded against its companion, 3, enters holes d d' and serves as a dowel, as will be understood by referring to the drawings. That portion of the hinge-plate a between hole d and the point where pin e rests when the rule is folded I form as a curved gradually-inclined plane, f . When the rule is completely folded, the end of pin e is at the base of said incline; but when sections 2 3 are swung open said pin gradually rises 55 until it reaches and enters hole d . By varying the location of hole d the rule may be locked at other degrees of inclination, or a series of holes may be provided and the rule utilized as a bevel. 60

After having used my described device as a square it may be returned to its folded position or extended for further use as a rule by simply withdrawing pin e from the holes d d' . The addition of such a locking device does 65 not interfere with the perfect working of the rule and does not add materially to the cost of construction.

Having described my invention, I claim—

A four-fold rule having one leaf of its main 70 hinge formed with a curved inclined way terminating with a hole, d , as set forth, a companion hinge-leaf having a hole, d' , that may be brought into coincidence with said hole d , and a dowel-pin carried by the folding-rule 75 section 5, adapted to engage said holes, substantially as and for the purpose specified.

JUSTUS A. TRAUT.
